METHOD OF MAKING BRISTLES FOR STREET SWEEPING BROOMS

Leo L. Lechene, Hazel Park, Mich. (Irvington, Pa.)

Filed Mar. 14, 1958, Ser. No. 721,573

2 Claims. (Cl. 300—21)

The invention pertains to the making or refilling of power-driven brooms of the kind used to sweep the pavement of roads and streets. A conventional broom of this type includes a cylindrical core made of wood or metal. The core is adapted to be mounted for rotation about its axis, and is provided with a spiral groove in its cylindrical surface, said groove extending from one end of the cylinder to the other. The core made in this manner serves as a means for support of bristles which are secured to said core and extend radially therefrom. The term bristles is used generally to identify thin, resilient, but hard and stiff fibers, strips, or wires which may be made of plastic materials.

To be applied to the core, the bristles are placed over the groove crosswise thereto, whereupon a cable is drawn over the bristles, midway their respective ends, to force the midportion of the respective bristles into the groove. In the process, under the pressure of the cable, each bristle is bent upon itself in a hairpin fashion, the looped portion of each bristle being wedged tight into the groove by the cable.

In this manner of operation bristles are applied to the core fistful by fistful, and the rotation of the core must be stopped prior to the application of each new fistful of the bristles to the core. What is to be noted is that the bristles, prior to their being bound to the core, are not bound or bonded together in any manner. This applies also to the bristles which are applied to the core by means of a machine.

The present invention pertains to a method of making bristles out of plastic sheet stock, which stock has the form of long bands or ribbons. More specifically, the method includes, as a part thereof, intersecting the body of one band or a plurality of bands in a stacked-up condition by a plurality of cuts transversely to the length of the bands, but leaving a portion of the bands, midway the side edges thereof, in an uncut condition.

The object of the invention is to provide a band including a multiplicity of bristles extending laterally from said midportion and integrally connected thereto. The purpose of this operation is to provide an assembly of bristles in the form of a band which may be fed from a reel to the core of a broom in order that it may be bound to the core by a cable in a manner analogous to that described above.

I shall now describe my invention with reference to the accompanying drawings in which:

Fig. 1 is a perspective view of a short length of a composite band consisting of a plurality of flexible bands stacked upon each other;

Fig. 2 is an enlarged perspective view of a part of said composite band after portions of the bands have been fused to each other, the view including a transverse sectional view of said composite band;

Fig. 3 is a perspective view of a short length of the composite band, portions of which have been split by a multiplicity of transverse cuts;

Fig. 4 is a top elevational view of a part of a core

of a broom and a short length of the composite band as it is applied to said core.

Similar numerals refer to similar parts throughout the several views.

- 5 The method of making such an assembly of bristles calls for a plurality of bands made of plastic material, such as nylon in sheet form, the preferred thickness of individual sheets ranging from $\frac{1}{16}$ to $\frac{1}{8}$ of an inch. The bands are to be stacked one upon the other to form 10 a composite band in which the respective side edges of the bands are aligned with each other.

Such a composite band is shown in Fig. 1 in which individual or component bands are marked 10. As the next step the bands so stacked are to be connected to each other all along a midportion intermediate the side edges of each component band. This is best accomplished by having the component bands fused to each other by application of heat till said midportions of the individual bands have been fused. The result of 20 such a fusion is shown in Fig. 2 in which numeral 12 shows a fused portion of the composite band, while the remaining portions of each band laterally extending from the solid portion are left detached from each other.

After the bands 10 have been so connected to each 25 other to form a composite band, said band is cut laterally to its length by a multiplicity of parallel cuts limited to the areas from the fused portion to the respective side edges 13 of the band, the lines 14 of the 30 respective cuts being spaced from each other to such distance as would amount to a satisfactory width of individual bristles to be used in the completed broom. The cutting operation of the composite band may be carried out by any suitable means.

As a result of the above operation the composite 35 band will be transformed into a solid ribbon, this being the fused portion 12, and a multiplicity of bristles 15 integrally connected thereto and extending laterally from the respective sides of said fused portion. Once the composite band has been so transformed, it may be 40 wound upon a reel from which it may be fed to the core of a broom. Such a core, marked 16, is shown in fragment in Fig. 4. The composite band which may be fed to the core is marked 17, while the cable by means of which the composite band is secured to the core is marked 18.

It will be understood that the fusing of the component bands 10 to each other is a preferred method of joining them to each other, but that this may be also effected by means of adhesives or by other suitable means.

50 After having described my improvement, what I wish to claim is as follows:

1. The method of making an assembly of bristles for rotary brooms out of plastic sheet stock in the form of bands, the method consisting of stacking the bands 55 upon each other lengthwise to form a composite band in which the side edges of the component bands are aligned with each other, applying heat to the composite band along a relatively narrow portion midway the side edges of the composite band to fuse the individual bands 60 along said midportion to each other from one end of the composite band to the other, but leaving unfused in each band the portions extending laterally from the fused portion, allowing the fused portion to cool off and to solidify, splitting said unfused portions by a plurality of parallel cuts transversely to the length of the 65 band, the cuts being spaced from each other to the distance equal to the desired width of the bristles, applying said band lengthwise and tangentially to a broom core having a helical groove therein with its fused central portion in registry with said groove, and tightly winding a wire over the band lengthwise thereof into said groove forming said band transversely into U-shape

so that the bristles project radially of the core throughout its length following said helical groove.

2. The method of making an assembly of bristles for rotary brooms out of plastic sheet stock in the form of bands, the method consisting of stacking the bands upon each other lengthwise to form a composite band in which the side edges of the component bands are aligned with each other, bonding each band along its midportion lengthwise to adhere to the corresponding portion of the adjoining band or bands, but leaving portions of each band extending laterally from said bonded portion unconnected, splitting said unconnected portions of all the bands by a multiplicity of straight cuts transversely to the length of the band, the cuts being spaced from each other by a distance equal to the desired width of individual bristles, applying said band lengthwise and tan-

gentially to a broom core having a helical groove therein with its fused central portion in registry with said groove, and tightly winding a wire over the band lengthwise thereof into said groove forming said band transversely into U-shape so that the bristles project radially of the core throughout its length following said helical groove.
